P. S. EASTERDAY,
REINFORCED CONCRETE CONSTRUCTION,
APPLICATION FILED MAY 24, 1916.

1,226,954.

Patented May 22, 1917.

UNITED STATES PATENT OFFICE.

PHILIP S. EASTERDAY, OF PORTLAND, OREGON.

REINFORCED CONCRETE CONSTRUCTION.

1,226,954.

Specification of Letters Patent. Patented May 22, 1917.

Application filed May 24, 1916. Serial No. 99,643.

To all whom it may concern:

Be it known that I, PHILIP S. EASTERDAY, a citizen of the United States, residing at Portland, in the county of Multnomah and State of Oregon, have invented certain new and useful Improvements in Reinforced Concrete Construction; and I do hereby declare the following to be a full, clear, and exact description of the invention, such as will enable others skilled in the art to which it appertains to make and use the same.

The present invention relates to improvements in reinforced concrete construction, and consists more particularly in improved coupling elements to be embedded, during manufacture, in sections of concrete pipes, culverts, and the like, for securing such sections together to form a continuous conduit. It is an object of the present invention to provide an improved coupling between the sections of concrete conduits which will form an elastic union, permitting the free expansion and contraction of the sections without the likelihood of causing rupture or breakage in the piping such as is commonly found to be the result where rigid couplings are employed; and by reason of such elastic couplings the sections of the conduit are made relatively yieldable to conform to a vertically curved grade line without fracture.

A further object of the present invention resides in providing an improved reinforced concrete construction of the above character, wherein the coupling elements will be constituted of rods bent to provide elastic inter-engaging coils and loops for receiving an elastic pin or wedge, through which the connection is effected, the rods being shaped from said coils and loops into divergent arms which are embedded in the concrete of the conduit sections, and have hooked ends to engage metal reinforcing elements in the sections.

The present invention constitutes an improvement over the construction shown and described in my prior Patent No. 1,061,665, granted May 13, 1913, and entitled "Coupling for reinforced concrete conduit sections".

In the accompanying drawings forming a part of this application, and in which similar reference symbols indicate corresponding parts in the several views:

Figure 1 shows two abutting conduit sec-

tions of reinforced concrete, with my invention applied thereto; the upper section being shown in horizontal section and the concrete body of the lower section being partly broken away.

Fig. 2 is an enlarged detail section on an axial plane of the connected conduit sections, showing the improved elastic coupling.

Fig. 3 is an enlarged sectional view on the same plane with Fig. 2, and illustrating a single section with one of the coupling elements embedded therein.

Fig. 4 is a perspective view of the inter-engaged coupling elements.

Figs. 5 and 6 are perspective views of the coupling elements shown disengaged; and

Fig. 7 is a perspective view of the coupling pin or wedge.

Referring more particularly to the drawings, in Fig. 1 there is illustrated at 1 and 2 abutting sections of concrete piping or culvert; the sections being reinforced preferably by the construction illustrated which embodies circumferentially and, uniformly axially spaced rods 3, about which are wound, tied, or secured in any other manner, diagonally extending wires 4.

It will be understood that any other suitable reinforcing arrangement may be embedded in the sections of the conduit as found desirable or necessary, the construction shown being that preferably employed in practice with good results, and which affords a secure hold for the hooked ends of the coupling elements.

These coupling elements are constructed for complementary engagement, one series of such elements projecting beyond one end of the conduit section, while the companion coupling elements have their engaging ends disposed in slots or recesses in the opposite end of the concrete section for receiving the projecting ends of the complementary elements on the next adjacent section. Such coupling elements are preferably formed from single lengths of rods or wires, one series of such elements being shaped after the manner shown in Fig. 5, where the rod is centrally returned upon itself to provide a loop 5, which projects, as shown in Fig. 1, beyond the pipe section; and from such loop 5 the rod is bent to provide divergent arms 6 and 7 extending through and embedded in the concrete material, the terminal ends of the arms 6 and 7 being bent to

105

110

provide hooks 8 and 9 for engaging the rods 3 of the concrete reinforcing work.

The complementary coupling element, as shown in Fig. 6, is also formed of a single length of rod bent centrally to provide a pair of coaxial spaced coils 10 and 11 for receiving the projecting loops 5 of the elements shown in Fig. 5, such coils 10 and 11, as more particularly disclosed in Figs. 2, 10 and 3, being disposed within slots or recesses 12 in the end of the culvert sections. Openings 13 communicate with the recesses 12 for admitting the loops 5 when the concrete sections are assembled in the manner shown 15 in Fig. 2. From the coils 10 and 11 the rod is bent into divergent arms 14 and 15, which are embedded in the concrete, and at its terminal ends the rod is formed into hooks 16 and 17 similar to the hooks 8 and 20 9 shown in Fig. 5, and for engaging the rods 3 in a similar manner, as shown in Fig. 1.

In Fig. 7 is shown a coupling pin or wedge similar to that shown and described 25 in my aforesaid prior patent, such pin being formed of a resilient rod wound spirally to provide a coaxial series of coils 18, of tapered or triangular form having flat bases 19 and rounded apexes 20; said elastic pin 30 being adapted to be driven or tightly forced between the interengaging loops 5 and coils 10 and 11 to thereby securely hold the conduit sections together; and at the same time provide an elastic coupling therefor, yielding, when required, to permit expansion and 35 contraction of the sections and to permit the same to conform to a changing grade line.

It will be understood that the recesses 12 are to be left free of any filling or other 40 material to permit the elastic action both in the coupling pin and in the coils 10 and 11 of the elements to expand and contract without interference, although such recesses 12 may be rendered inaccessible to dirt and 45 other foreign matter by placing caps thereover.

It is obvious that those skilled in the art may vary the details of construction and

arrangements of parts without departing from the spirit of my invention, and therefore I do not wish to be limited to such features except as may be required by the 50 claims.

I claim:

1. The combination with a plurality of 55 concrete sections provided with a wire mesh reinforcement, of a series of rods bent in substantially U-shaped form and having hooked ends engaging said wire reinforcement, said rods being embedded in said 60 concrete section, the loop of one of said rods projecting beyond the face of the concrete section, and the loop of the other of said rods being screened in the opposite end of the concrete section, each of said loops 65 being adapted to register with the loop of the adjacent section, and a resilient coupling pin formed of a single rod bent in the form of a series of continuous U's closed at the top and adapted to project into the 70 loops of the coupling rods and couple the same together in resilient relation, substantially as described.

2. The combination with a plurality of 75 concrete sections provided with a wire mesh reinforcement, of a series of rods bent in substantially U-shaped form and having hooked ends engaging said wire reinforcement, said rods being embedded in said concrete sections, the loop of one of said rods 80 projecting beyond the face of the concrete section, and the loop of the other of said rods being screened in the opposite end of the concrete section and being in the form of a closed elliptical spiral, each of said loops 85 being adapted to register with the loop of the adjacent section, and a resilient coupling pin formed of a single rod bent in the form of a series of continuous U's closed at the top to project into the loops of the 90 coupling rods and couple same together in resilient relation, substantially as described.

In testimony whereof, I affix my signature.

PHILIP S. EASTERDAY.
